UNITED STATES PATENT OFFICE.

CHARLES H. SMITH, OF SPOKANE, WASHINGTON.

WHEEL-FLANGE OILER.

1,161,897.

Specification of Letters Patent. Patented Nov. 30, 1915.

Application filed February 24, 1914. Serial No. 820,699.

To all whom it may concern:

Be it known that I, CHARLES H. SMITH, a citizen of the United States, residing at Spokane, in the county of Spokane and State of Washington, have invented new and useful Improvements in Wheel-Flange Oilers, of which the following is a specification.

This invention relates to improvements in wheel flange oilers.

It is one of the objects of this invention to provide a wheel flange oiler, which will operate to lubricate a wheel flange irrespective of the character of rail which it traverses, that is, irrespective as to whether or not the rail is straight or curved.

A further object is to provide a flange lubricator or oiler, which will be held in its most efficient discharging position by gravity, and it is also contemplated to provide an oiler wherein the oil feed or discharge as regards efficiency will be maintained as the parts wear, so as to avoid under or over discharge.

Other objects and features of the invention will be more fully described in connection with the accompanying drawings, and will be more particularly pointed out in and by the appended claims.

In the drawings:—Figure 1 is a view in end elevation of a portion of a truck and a car body, illustrating the application of one form of my invention. Fig. 2 is a plan sectional view of an improved form of supporting bracket. Fig. 3 is an enlarged detail view, partly in section and partly in elevation of the reservoir of the oiler. Fig. 4 is a perspective view of the discharge pipe.

Like characters of reference designate similar parts throughout the different figures of the drawings.

As illustrated, 1 designates a car body and 2 designates a portion of a truck frame, the truck wheel being indicated at 3.

I mount upon one member of the truck frame, rigidly, a bracket section 4 which is provided with an attaching end 5 adapted to be secured to the truck frame by means such as screws or bolts. The bracket section 4 is bifurcated, as indicated at 6, and be-

tween the forked bifurcated end I pivot one end of a movable bracket section 7, by means of a pivot bolt 8. The movable bracket section 7 is shown provided with bent terminals 9 and 10, disposed in angular relation 55 with respect to each other, and to both of which may be secured attaching hooks 11 by means of nuts 12.

My improved oiling device includes a reservoir 13, which is provided with a diaphragm 14 having a valve seat aperture 15. I preferably make the reservoir in two parts and embody the diaphragm in a base portion 16, which is threaded on the upper portion 13 as indicated at 17. The base 16 is threaded to receive a threaded valve stem 18 on the end of which a closure 19 is formed to engage the valve seat aperture 15 and regulate the flow of oil. In order to retain the valve stem in an adjusted position, I provide 60 a lock nut 20, which is equipped with a hand grip 21 to facilitate tightening the nut in a stem locking position. The outer end 22 is provided with handle projections 23 for turning the stem. A discharge pipe is provided with or includes an elbow 24 having a threaded end 25 adapted to be turned into a reduced internally threaded portion 26 of the base 16. Said pipe includes a second elbow 27, which connects the first-named or 65 attaching elbow 24 with a straight length of pipe 28 thereby constituting an intermediate elbow. The end 29 of the straight section 28 is disposed at an angle to the longitudinal axis of section 28, for a purpose 70 which will presently appear. The connecting, intermediate and straight lengths are rigidly connected, but the provision of the two elbows enables a relatively wide range 75 of adjustment, when the parts are originally 80 assembled, to dispose the chamfered or angular discharge end 29 in such a manner that it will engage the wheel flange throughout the circumference of the discharge end. As 85 will be seen by reference to Fig. 1, the hooks 90 95 11, or rather one thereof, engage the connecting elbow 24 adjacent the reduced nipple end 26 to detachably but rigidly connect the movable bracket section 7 and the oil reservoir and pipe. In the construction shown, I 100

mount the rigid section 4 upon an upright bracket 30, which latter is secured to a portion 31 of the truck frame.

The weight of the movable bracket section 5 and the parts which are connected thereto will normally cause gravity engagement of the chamfered end 29 against the wheel flange, as shown in Fig. 1, and it is one of the features of this invention that relative 10 displacement of the truck with respect to the car body will not in any way interfere with a feed engagement of the pipe end 29 with the wheel flange, and therefore a limited but continuous feed will be effected 15 irrespective of whether or not the truck is rounding a curved stretch of track. Thus it will be seen that I provide a unitary oiling structure which is mounted wholly upon the truck and which is normally maintained in 20 a feeding position by gravity and wherein the feed of lubricant is also effected by gravity.

Wear of the chamfered flange engaging end 29 as a result of contact with the wheel flange will provide a ground joint which will prevent discharge of lubricant when the wheel is at rest by reason of the effective engagement which the weight of the movable portion of the device provides. Thus it will 30 be seen that continued wear will not deteriorate or impair but will rather increase the efficiency of my device by reason of the fact that the softer material of the discharge pipe, with respect to the material of the car 35 wheel will cause the former to assume a discharge end contour conforming to the shape which the wheel flange takes as a result of wear, and after the elbow sections are correctly adjusted during initial installation, 40 no further adjustment will be necessary.

It will not be necessary to equip each wheel of each truck of a car or train with my improved oiler inasmuch as the leading wheel of a car will be lubricated sufficiently 45 to supply following wheels by reason of the supply applied to the track, and it will be further noted, that the improved device of my invention serves to deliver the oil to the flange in a manner to lubricate the ball of 50 the rail and not the face thereof.

While I have herein shown and described one specific form of my invention, I do not wish to be limited thereto except for such limitations as the claims may import.

55 I claim:—

1. In a wheel flange oiler for car trucks, an oil supply device comprising an oil reservoir and a pipe depending therefrom for endwise abutting engagement against the 60 wheel flange, and means pivotally supporting said device on the truck for gravity swinging movement to engage the discharge end of the pipe with the wheel flange irre-

spective of the character of the rail traversed by the wheel, substantially as described.

2. In a wheel flange oiler for car trucks, an oil supply device comprising an oil reservoir and a pipe depending therefrom and having a flange engaging end chamfered with respect to the axis of the said pipe, and means movably supporting said device on said truck for gravity swinging movement of the device to engage the chamfered discharge end against the wheel flange, substantially as described.

3. In a wheel flange oiler for car trucks, an oil supply device comprising an oil reservoir and a pipe extending therefrom, and means movably supporting said device on said truck for gravity movement of the device to engage said pipe in endwise abutting relation against the wheel flange, substantially as described.

4. In a wheel flange oiler for car trucks, an oil supply device comprising an oil reservoir and a pipe extending therefrom and composed of softer material than that of the wheel flange, and means movably supporting said device on said truck for gravity movement of the device to engage said pipe in endwise abutting relation against the wheel flange, whereby wear will shape the end of the pipe to conform to the shape of the flange, substantially as described.

5. In a wheel flange oiler for car trucks, an oil supply device comprising an oil reservoir and a pipe extending therefrom and having a discharge end at an angle to its axis other than at a right angle thereby providing a discharge end of oblong contour, and means movably supporting said device on said truck for gravity movement of the device to engage said pipe in endwise abutting relation against the wheel flange with the major axis of the discharge end disposed circumferentially of the flange, substantially as described.

6. In a wheel flange oiler for car trucks, an oil supply device comprising an oil reservoir and a pipe structure extending therefrom and comprising elbow sections and a straight section with the discharge end of the straight section at an angle to the longitudinal axis of the straight section, and means movably supporting said device on said truck for gravity movement of the device to engage the discharge end in endwise abutting relation against the wheel flange, substantially as described.

7. In a wheel flange oiler for car trucks, an oil supply device comprising an oil reservoir and a pipe structure extending therefrom and comprising elbow sections and a straight section having threaded connection with each other to form an oil conduit, and

means movably mounting said device on the truck comprising a bracket section fixed to the truck and a bracket section fixed to the device and pivoted to the first-named bracket section for gravity movement of the device to engage the pipe in endwise abutting relation against the wheel flange, substantially as described.

Copies of this patent may be obtained for five cents each, by addressing the "Commissioner of Patents, Washington, D. C."

In testimony that I claim the foregoing as my own, I hereby affix my signature in the presence of two subscribing witnesses.

CHARLES H. SMITH.
